F. S. Giles,

United States Patent Office.

FAYETTE S. GILES, OF NEW YORK, N. Y., ASSIGNOR TO GILES, WALES & CO., OF SAME PLACE.

Design No. 3,886, dated March 8, 1870.

DESIGN FOR THE BARREL-BRIDGE, RATCHET-CAP BASE, AND ARBOR-CUP OF WATCHES.

The Schedule referred to in these Letters Patent and making part of the same.

To all whom it may concern:

Be it known that I, FAYETTE S. GILES, of the city, county, and State of New York, have invented a new Design for the Band-Bridge Ratchet-Cap Base, and Arbor-Cup of Watches; and I do hereby declare that the following is a full, clear, and exact description of the same, reference being had to the accompanying drawings forming part of this specification.

The drawing represents not only the barrel-bridge and the attached parts embraced in the design, but also represents the top-plate and cock, the better to show the application of the design.

Figure 1 is a top view, and

Figure 2, a profile perpendicular to fig. 1 in the plane indicated by the line $x x$.

Similar letters of reference indicate corresponding parts in both figures.

The general form of the barrel-bridge A is that of a straight bar widened at one end, as shown at $a b$ in fig. 1, and having both its ends of arc-form, to conform to the case of the watch.

The widened portions $a b$ have their inner edges hollowed out in the form of arcs to conform to the circumference of the spring-barrel.

The ratchet-cap B is in the form of a circle, of a diameter considerably larger than the width of that part of the bridge next to which it is situated.

The base C is in the form of a circle, somewhat smaller than the ratchet-cap, and projects above the ratchet-cap, as shown at c in fig. 1.

The arbor-cup D stands up above the base C in the form of a hollow cylinder with a small fillet, d , at its union with the base.

What I claim and desire to secure by Letters Patent, is—

The design herein described and represented in the accompanying drawings of the barrel-bridge, ratchet-cap, base, and arbor-cup of a watch.

F. S. GILES.
